UNITED STATES PATENT OFFICE.

ROLAND P. PLACE, OF MIDLAND, MICHIGAN.

EMERY-WHEEL DRESSER.

Application filed February 9, 1925. Serial No. 7,804.

This invention relates to the construction of rotatable dressing cutters for emery wheels, and its object is to produce bearings for a device of this character which will eliminate the objectionable "chatter" so commonly experienced when dressing tools are in use which "chatter" results in high spots and ridges on the surfaces being dressed.

In the accompanying drawing, Fig. 1 is an end elevation of a dressing cutter and a section of the holder therefor. Fig. 2 is a longitudinal section of the cutter and of the support. Fig. 3 is an elevation of the cutter and a section of the support showing a slight modification of the shaft on which the cutter is mounted. Fig. 4 is a section and Fig. 5 is an elevation of a bushing. Fig. 6 is an elevation and a section of a spring washer on the line $w-w$.

Similar reference characters refer to like parts throughout the several views.

I have found that when the rotary cutters of dressing tools for grinding wheels are not positively prevented from moving laterally relative to the axes of the cutters that chattering occurs which results in high spots and ridges being formed on the surfaces being dressed, and that this may occur even when the slackness of the bearings and of the cutter shaft in the holder is no more than a few thousandths of an inch. It is for this reason that the head 1 of the holder is formed with tapering holes 2 and 3, and that the head 4 of the shaft 5 is turned to fit the hole 2, while a tapering and split bushing 6 fits the hole 3, so that, when this bushing is forced in by the nut 7, it firmly grips the shaft 5. When thus assembled, the shaft 5 cannot move or vibrate in the holder, being rigidly held therein.

The shaft may be forced into a sleeve 8 which receives the bearing rings 9 or this sleeve may be omitted and the rings 9 be fitted tightly on the shaft itself. The rings, the sleeve and the shaft must fit as tightly as possible, the rings being slidable inwardly under pressure. The bearing rings 10 are

pressed into the barrel 11 on which the star-shaped cutters 12 are held by the nut 13, the latter being held in place by the well known lock washer 14 having a finger 15. I prefer to use the sleeve 8 because it renders assembly and replacement more convenient.

Thin washers 17 fit the rings 9 and prevent the entrance of dust to the spaces between the balls 18. Other washers 19 are slidable on the shaft and contact with the bearing rings 9 and are pushed toward each other by the spring washers 20 which lie against the inner sides of the ends 21 of the holder and are provided with wings 22 that press against the washers 19. These washers 19 also assist in preventing the entrance of dust. These spring washers are tempered to have sufficient initial stiffness, the central holes 23 being so large that the washer will not contact with the tapering head 4 of the bolt or with the tapering bushing 6, as shown in Fig. 3, or the holes 23 may be smaller so that when the head 4 and bushing 6 are forced toward each other, the washers 20 will be carried with them and the pressure on the bearing rings 9 be thereby increased. In either case, there is no looseness at the ball bearings of the rotary cutter, this being entirely eliminated by the rigid shaft and the constant pressure of the spring washers.

The details and proportions of this cutter mounting may all be changed by those skilled in the art without departing from the spirit of my invention as set forth in the following claim.

I claim:—

In an emery wheel dresser, the combination of a holder having side members, a shaft mounted in said side members, a cutter mounted on the shaft, ball bearings between the shaft and cutter, washers on the shaft contacting with the inner ring members of said bearings, and cup-shaped resilient metal washers between said washers and the side members of the holder to automatically adjust said ball bearings.
